(Cl. D15—8)

To all whom it may concern:

Be it known that we, David Chapman and Richard G. Reineman, citizens of the United States, residing at Chicago, in the county of Cook, State of Illinois, and Muskegon, in the county of Muskegon, State of Michigan, have invented a new, original, and ornamental Design for a Combination Table-Chair Unit or the like, of which the following is a specification, reference being had to the accompanying drawings, forming a part thereof.

In the drawings:

Fig. 1 is a perspective view looking diagonally at the front of a combination table-chair unit or the like, showing our new design;

Fig. 2 is a perspective view looking at the right hand end of the unit of Fig. 1;

Fig. 3 is a front elevational view thereof.

The dominant features of our design are shown in full lines.

We claim:

The ornamental design for a combination table-chair unit or the like, as shown and described.

DAVID CHAPMAN.
RICHARD G. REINEMAN.
